UNITED STATES PATENT OFFICE.

ADOLPH KLAUNIG, OF NEWARK, NEW JERSEY.

LOCK.

SPECIFICATION forming part of Letters Patent No. 268,692, dated December 5, 1882.

Application filed May 17, 1882. (Model.)

To all whom it may concern:

Be it known that I, ADOLPH KLAUNIG, of Newark, in the county of Essex and State of New Jersey, have invented a new and useful improvement in Locks, of which the following is a specification.

My invention relates to self-locking trunk or drawer locks in which when the key has been turned in unlocking it may be taken out and the trunk, &c., be opened at any time thereafter, and the closing of the trunk or drawer will lock it; and it consists in the devices substantially as hereinafter set forth.

Figure 1 is a rear side view. Fig. 2 is the same, with the plate removed, showing the lock when locked. Fig. 3 is the same unlocked. Fig. 4 is the same, showing a modification adapting it for use as a drawer-lock. Fig. 5 is a detailed view of a catch as used in connection with a drawer-lock.

In my construction I attach to the plate A four stationary pins, B C D E. On the bolt H are two pins, F G. The pins D E are used as guides for the bolt, the former being on the lower edge of it and the latter working in the slot I. The tumblers a are hung on the pin D. There are two or more tumblers, fitting into different wards of the key K, making it more difficult to open the lock without the regular key. In opening, the key is placed on the stem or pin C in Fig. 2, and the bolt is moved to the right. In this movement a spring-lever, L, hung to the bolt on the pin G, is also carried to the right, and the rounded end strikes the catch m, and rises up into the slot n in the catch, (seen in Fig. 5.) On the pin G is also hung a shouldered stop, P, acted on by the spring Q, and when the bolt is car-

ried to the right, so that the catches S of said bolt are out of the catch m, this stop will drop down, and the shoulder will catch against the pin E and hold the bolt unlocked until the cover has been lifted up, so that after the bolt has been slid in unlocking the key may be taken out, and the locking again is prevented by the stop P; but the raising of the cover, carrying up the catches m, carries up also the end of the lever L, resting in the right-hand catch, until the catch is removed or passes the end of the lever. Then the spring O, acting on the other end of the lever, restores the lever to its former position. Then when the cover is again pressed down the catch m will press down the end of the lever, which will throw up the opposite end of this lever and throw up the stop, and allow the bolt again to engage the catch m by the action of the spring T, as seen in Fig. 2.

The provision for using the same lock for a drawer is in having, as shown in Fig. 4, a side cut, V, in the top of the plate A, whereby the catches m, when the drawer is slid in on a plane with the top of the lock, will engage the catches S of the bolt from the side instead of, as in a trunk, from the top. The catch m' in Fig. 5 shows a beveled side to slide on the catch.

I claim—

The bolt H, sliding on the guide-pins D E, lever L, stop P, hung on the pin G, and the springs O and Q, in combination with a key, K, and catches m, substantially as and for the purpose specified.

ADOLPH KLAUNIG.
